[57] **CLAIM**

The ornamental design for sanitary seals for covering liquid containing cans, as shown and described.

DESCRIPTION

FIG. 1 is a front, top and side perspective view of the sanitary seals for covering liquid containing cans showing my new design;

FIG. 2 is a front elevational view thereof, the rear being a mirror image of the front shown in FIG. 2;

FIG. 3 is an end elevational view thereof, the end opposite being a mirror image of the end shown in FIG. 3;

FIG. 4 is a top plan view thereof;

FIG. 5 is a bottom plan view thereof; and,

FIG. 6 is a perspective view of a single seal shown separately to indicate position of use.

The broken line showing of a can is for illustrative purposes only and forms no part of the claimed design.
